UNITED STATES PATENT OFFICE.

EDWARD E. HINRICHSEN, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,276,761.

Specification of Letters Patent. Patented Aug. 27, 1918.

Application filed May 22, 1917. Serial No. 170,308.

To all whom it may concern:

Be it known that I, EDWARD E. HINRICHSEN, a citizen of the United States, residing at New York, in the county of New York 5 and State of New York, have invented certain new and useful Improvements in Telephone-Exchange Systems, of which the following is a full, clear, concise, and exact description.

10 This invention relates to telephone exchange systems, and more particularly to such systems of the central energy type and is an improvement over the system disclosed in a copending application of C. W. Keck-
15 ler, Serial No. 170,603, filed May 24, 1917, in that less apparatus is required in accomplishing the same result, and in that an additional feature is embodied by which a calling supervisory signaling device of a link
20 circuit connected with a telephone line as a called line operates continuously as a ringing signal and later operates intermittently as a disconnect signal.

By the embodiment of these features in a
25 system the same character of signal is always presented to an operator when an act upon her part for the benefit of the subscriber is called for, while, when an act which is not for the benefit of the subscriber
30 is called for, a signal of a different character or manifestation is furnished. In this way the possibility of confusion in interpreting signals is avoided.

For a more complete understanding of
35 this invention, reference should be had to the following description taken in connection with the accompanying drawing, wherein there are shown two telephone lines A and B extending from subscribers' stations and
40 terminating at a central office at which is located a link or cord circuit C containing one embodiment of this invention, and employed for interconnecting the telephone lines. It is thought that the nature of this invention is
45 such that a proper understanding thereof will be had from a description of the operation of the system shown in the drawing; hence it will be so described.

Subscriber A in initiating a call in the
50 usual manner causes the lighting of line lamp 5, and the operator upon observing the lighted condition thereof inserts answering plug 35 of the cord circuit into line jack 7. Thereupon answering supervisory lamp 37
55 lights and relay 36 and cut-off relay 6 oper-

ate over a circuit from battery through the lamp 37, left-hand winding of relay 36, sleeve contacts of the answering plug 35 and line jack 7, and the winding of cut-off relay 6 to ground. The lighted condition 60 of the answering supervisory lamp 37 is an indication to the operator that the cord circuit is connected with the line of a calling subscriber and that this call has not been attended to. This, of course, calls for an act 65 upon the part of the operator for the benefit of the subscriber. The energization of answering supervisory relay 38 also resulted from the insertion of the answering plug 35 into the link jack 7.

The operator may now actuate listening key 39 to connect the operator's telephone set to the cord circuit, and, in so doing, closes a contact 40, which establishes a circuit through right-hand winding of relay 70 36 in parallel with the lamp 37. The windings of relay 36 are differentially connected so that, upon the establishment of this circuit through its right-hand winding the relay is deenergized, releasing its armatures, 80 thereby establishing a maintaining circuit through its right-hand winding which includes the right-hand normal contact of relay 36 and the alternate contact of supervisory relay 38. Since the right-hand winding of relay 36 is connected in parallel with the lamp 37, this lamp is effaced, and remains effaced until the answering supervisory relay 38 is deenergized and relay 36 85 energized.

The operator may, upon being advised of the number of the line with which connection is desired and assuming it to be line B, restore the listening key to normal position, and insert the calling plug 45 into line 95 jack 42 of line B, whereupon calling supervisory lamp 47 is lighted and cutoff relay 44 operated. The subscriber on the line B may now be signaled by actuating a ringing key 41. In response, the called subscriber removes the receiver from the switchhook and causes the operation of calling supervisory relay 48, which connects the left-hand winding of a relay 46 in parallel with the lamp 47, thereby effacing the lamp. The 100 establishment of the circuit through left-hand winding of relay 46 causes the operation of this relay, which, in operating, completes a locking circuit for itself, which may be traced from battery through the 110

lamp 47, the right-hand winding of relay 46, right-hand alternate contact thereof, sleeve contacts of calling plug 45 and line jack 42, and the winding of cut-off relay 5 44 to ground. The lamp 47 is shunted by the left-hand winding of relay 46 and is therefore effaced.

At the conclusion of the conversation, when the calling and called subscribers A 10 and B restore their receivers to the switch-hooks, causing the deenergization of the supervisory relays 38 and 48, the deenergization of the former opens the circuit including the right-hand winding of relay 36, 15 which, thereupon, due to a flow of current through its left-hand winding, attracts its armatures, connecting interrupter 50 and resistance 51 in parallel with the answering supervisory lamp 37. Due to the rotation 20 of the interrupter 50, the lamp is intermittently shunted, thereby causing the intermittent lighting of the lamp to furnish a disconnect signal. This path, in parallel with the lamp 37, may be traced from battery through interrupter 50, resistance 51, left-hand alternate contact of relay 36, normal contact of relay 38 to the upper terminal of the lamp. The deenergization of 25 the calling supervisory relay 48 connects interrupter 50 and resistance 52 in parallel with the lamp 47, thereby causing the intermittent lighting of the calling supervisory lamp to furnish a disconnect signal. The operator, in response thereto, may 30 withdraw the plugs from the jacks, restoring all apparatus to normal condition.

However, should the calling subscriber, before the plugs are withdrawn from the jacks, remove the receiver from the switch-hook to initiate another call, the resulting 40 energization of the answering supervisory relay 38 disconnects resistance 51 and interrupter 50 from circuit relation with the lamp 37, thereby permitting the answering supervisory lamp to be lighted continuously 45 to furnish a recall signal to the operator. In response to this signal, the operator may actuate listening key 39, causing the deenergization of relay 36, as before described. The connection may then be completed with the line desired by first withdrawing the calling plug from line jack 42, thereby deenergizing relay 46 and effacing calling supervisory lamp 47, and then inserting the calling plug into the jack of the 50 desired line.

What is claimed is:

1. A telephone exchange system comprising a telephone line, a link circuit, a signaling device in the link circuit, a supervisory relay and a secondary relay in the link circuit energized upon connection of the link circuit with the line as a calling line, an operating circuit for the signaling device established upon the energization of both re- 60

lays, an operator-controlled switch actuated to cause the deenergization of this secondary relay to disable the operating circuit of the signaling device, and interrupter mechanism brought into circuit with the signaling device upon the subsequent deenergization of the supervisory relay and the energization of the secondary relay. 70

2. A telephone exchange system comprising a telephone line, a link circuit, a signaling device in the link circuit, a supervisory relay and a secondary relay in the link circuit energized upon connection of the link circuit with the line as a calling line, an operating circuit for the signaling device established upon the energization of both relays, an operator-controlled switch actuated to cause the deenergization of this secondary relay, a shunt circuit for the signaling device established upon the deenergization of the secondary relay while the supervisory relay is energized, and an interrupter mechanism included in a shunt circuit of the signaling device upon the subsequent deenergization of the supervisory relay and the energization of the secondary relay. 80

3. A telephone exchange system comprising a telephone line, a link circuit, a signaling device in the link circuit, a supervisory relay and a secondary relay in the link circuit energized upon connection of the link circuit with the line as a calling line, an operating circuit for the signaling device established upon the energization of both relays, an operator's telephone set, a switch for connecting the operator's telephone set with the link circuit and when actuated causing the deenergization of the secondary relay, a shunt circuit for the signaling device established upon the deenergization of the secondary relay while the supervisory relay is energized, an interrupter mechanism included in a shunt circuit of the signaling device upon the subsequent deenergization of the supervisory relay followed by the energization of the secondary relay. 90

4. A telephone exchange system comprising a telephone line, a link circuit, a signaling device in the link circuit, a supervisory relay and a secondary relay in the link circuit energized upon connection of the link circuit with the line as a calling line, an operating circuit for the signaling device established upon the energization of both relays, an operator-controlled switch actuated to cause the deenergization of the secondary relay, a shunt circuit for the signaling device established upon the deenergization of the secondary relay while the supervisory relay is energized, and another shunt circuit for the signaling device including interrupter mechanism and contacts of both relays established upon the de- 100

energization of the supervisory relay followed by the energization of the secondary relay to cause the intermittent operation of the signaling device.

- 5 5. A telephone exchange system comprising a telephone line, a link circuit, a signaling device in the link circuit, a supervisory relay and a secondary relay in the link circuit energized upon connection of
- 10 the link circuit with the line as a calling line, an operating circuit for the signaling device established upon the energization of both relays, an operator's telephone set, a switch for connecting the operator's telephone set with the link circuit and when actuated causing the deenergization of the secondary relay, a shunt circuit for the signaling device established upon the deenergization of the secondary relay while the
- 15 supervisory relay is energized, and another shunt circuit for the signaling device including interrupter mechanism and contacts of both relays established upon the deenergization of the supervisory relay followed
- 20 by the energization of the secondary relay to cause the intermittent operation of the signaling device.
- 25

6. A telephone exchange system comprising a telephone line, a link circuit, a signaling device in the link circuit, a supervisory relay and a secondary relay in the link circuit energized upon connection of the link circuit with the line as a calling line, an operator-controlled switch actuated to deenergize the secondary relay, interrupter mechanism included in circuit with the signaling device upon the deenergization of the supervisory relay followed by the energization of a secondary relay to cause the intermittent operation of the signaling device to furnish a disconnect signal, and an operating circuit for the signaling device rendered effective upon the subsequent energization of the supervisory relay to cause the continuous operation of the signaling device to furnish a recall signal.

7. A telephone exchange system comprising a telephone line, a link circuit, a signaling device in the link circuit, a supervisory relay and a secondary relay in the link circuit energized upon connection of the link circuit with the line as a calling line, an operator-controlled switch actuated to de-
50 energize the secondary relay, a shunt circuit including interrupter mechanism established for the signaling device upon the deenergization of the supervisory relay followed by the energization of the secondary relay to
55 cause the intermittent operation of the signaling device to furnish a disconnect signal, and an operating circuit for the signaling device rendered effective upon the subsequent energization of the supervisory relay to cause the continuous operation of
60
65

the signaling device to furnish a recall signal.

8. A telephone exchange system comprising a telephone line, a link circuit, a signaling device in the link circuit, a supervisory relay and a secondary relay in the link circuit energized upon connection of the link circuit with the line as a calling line, an operator-controlled switch actuated to de-energize the secondary relay, an intermittently closed operating circuit for the signaling device established upon the de-energization of the supervisory relay followed by the energization of the secondary relay to cause the intermittent operation of the signaling device to furnish a disconnect signal, and an operating circuit for the signaling device rendered effective upon the subsequent energization of the supervisory relay to cause the continuous operation of the signaling device to furnish a recall signal. 70 75 80 85

9. A telephone exchange system comprising a telephone line, a link circuit, a signaling device in the link circuit, a supervisory relay and a secondary relay in the link circuit energized upon connection of the link circuit with the line as a calling line, an operator-controlled switch actuated to deenergize the secondary relay, an intermittently closed operating circuit for the signaling device including contacts of both relays established upon the deenergization of the supervisory relay followed by the energization of the secondary relay to cause the intermittent operation of the signaling device to furnish a disconnect signal, and an operating circuit for the signaling device rendered effective upon the subsequent energization of the supervisory relay to cause the continuous operation of the signaling device to furnish a recall signal. 90 95 100 105

10. A telephone exchange system comprising a telephone line, a link circuit, a signaling device in the link circuit, an operating circuit for the signaling device established upon the connection of the link circuit with the line as a called line to cause the continuous operation of the signaling device, a supervisory relay in the link circuit, a secondary relay energized upon the energization of the supervisory relay, a shunt circuit for the signaling device including a winding of the secondary relay established upon the energization of the supervisory relay to disable the signaling device, and a second shunt circuit including interrupter mechanism substituted for the first-mentioned shunt circuit upon the subsequent de-energization of the supervisory relay to cause the intermittent operation of the signaling device. 110 115 120 125

11. A telephone exchange system comprising a telephone line, a link circuit, a signaling device in the link circuit, an operating circuit for the signaling device established 130

upon the connection of the link circuit with the line as a called line to cause the continuous operation of the signaling device, a supervisory relay in the link circuit, a shunt circuit for the signaling device established upon the energization of the supervisory relay to disable the signaling device, a secondary relay energized by the establishment of the shunt circuit, a locking circuit for the 10 secondary relay established upon the ener-

gization thereof, and a second shunt circuit including interrupter mechanism substituted for the first-mentioned shunt circuit upon the subsequent deenergization of the supervisory relay to cause the intermittent operation of the signaling device. 15

In witness whereof, I hereunto subscribe my name this 18th day of May, A. D., 1917.

EDWARD E. HINRICHSEN.
